UNITED STATES PATENT OFFICE.

WILLIAM M. CONSELMAN, OF LOS ANGELES, CALIFORNIA.

DESIGN FOR A DOLL.

Application filed January 5, 1926. Serial No. 15,958. Term of patent 7 years.

To all whom it may concern:

Be it known that I, WILLIAM M. CONSELMAN, a citizen of the United States, and a resident of Los Angeles, county of Los Angeles, and State of California, have invented a certain new, original, and ornamental Design for Dolls; and I do hereby declare that the following is a full, clear, and exact specification thereof, reference being had to the accompanying drawings, forming a part hereof.

I claim:

The ornamental design for a doll as shown.

In witness whereof, I have hereunto affixed my signature.

WILLIAM M. CONSELMAN.
